UNITED STATES PATENT OFFICE

169,855

RAILWAY CAR BODY

Stanley W. Kay, Chicago, Ill., assignor to Pullman-Standard Car Manufacturing Company, Chicago, Ill., a corporation of Delaware

Application June 27, 1952, Serial No. 20,375

Term of patent 14 years

(Cl. D66—1)

To all whom it may concern:

Be it known that I, Stanley W. Kay, a citizen of the United States of America and resident of Chicago, county of Cook, and State of Illinois, have invented a new, original, and ornamental Design for a Railway Car Body, of which the following is a specification, reference being had to the accompanying drawings, forming part thereof.

In the drawings—

Fig. 1 is a perspective view of a railway car body in which my new design is incorporated, having portions broken away better to reveal the disposition of the upper level observation room within the vehicle and showing the supporting trucks in dotted lines;

Fig. 2 is a horizontal sectional view taken through a portion of the vehicle showing the upper level observation room in plan;

Fig. 3 also is a horizontal sectional view taken through the remaining portion of the vehicle, showing the upper level observation room in plan;

Fig. 4 is a vertical longitudinal sectional view through a portion of the vehicle, taken on the line 4—4 of Fig. 2, showing one side of the upper level observation room in elevation;

Fig. 5 also is a vertical longitudinal sectional view taken on the line 5—5 of Fig. 3 through the remaining portion of the vehicle, showing one side of the upper level observation room in elevation;

Fig. 6 is a vertical longitudinal sectional view through the vehicle taken on the line 6—6 of Fig. 2 in the passageway of the vehicle, showing the stair well to the upper level observation room in elevation;

Fig. 7 is a vertical longitudinal sectional view through the vehicle taken on the line 7—7 of Fig. 2, showing the opposite side of the vehicle from that illustrated in Fig. 5 in elevation; and

Fig. 8 is a perspective view of one end of the upper level observation room in the vehicle.

The characteristic features of the present design reside in the interior upper level observation room design shown in the drawings.

The dominant features of my design reside in the portions shown in full lines.

What is claimed is:

The ornamental design for a railway car body, substantially as shown and described.

STANLEY W. KAY.
